FIG. 9.

INVENTOR

RALPH W. JENKINS.

Thomas L. Ryan
ATTORNEY.

UNITED STATES PATENT OFFICE.

RALPH W. JENKINS, OF DALEVILLE, INDIANA.

SASH-RETAINER CASEMENT.

Application filed November 25, 1927. Serial No. 235,567.

This invention relates to improvements in sash retainer construction for the movable sashes of the windows of passenger cars, the invention being especially applicable to auto-
5 mobile, motor-bus, and railway-car bodies.

The objects of my invention are to provide a device of the kind referred to, which is simple and economical of construction and easy to install; which device while permitting 10 of the easy raising or lowering of the window sash, will retain same against vibration or dislodgement, and will constitute a weather-proof closure; and which will be dependable, strong and durable, and not liable to get out 15 of order or repair.

The above named general objects, as well as more specific purposes of the invention which will be apparent as the specification of my invention proceeds, are accomplished by, 20 and the invention is embodied in the new construction, combination and arrangement of parts described in the following specification, and illustrated in the accompanying drawings. The invention is defined in the append- 25 ed claims.

The several parts of the invention, as they appear in the different views in the drawings, are identified by suitable characters of reference applied to them.

30 In the drawings,—

Figure 1 is a front view of my improved sash retainer casement shown of width and length for a pillar of standard construction.

Figure 2 is a side view taken in the direc- 35 tion of the arrow 2 in Figure 1.

Figure 3 is an enlarged top plan view of Figure 1.

Figure 4 is a sectional top plan view taken on the line 4—4 in Figure 1.

40 Figure 5 is a side view of the sash retainer casement secured in place on a body pillar of standard form, the sash being shown in the raised position.

Figure 6 is an enlarged sectional plan view taken on the line 6—6 in Figure 5.

Figure 7 is an interior view of a panel of motor bus construction, showing the pillars thereof equipped with my improved sash retainer casements, the window sash being at 50 the raised position.

Figure 8 is a view showing the appearance of the exterior of the body construction and the window casement, as illustrated in Figure 7.

55 Figure 9 is a vertical cross sectional view taken on the line 9—9 in Figure 7.

In the present specification, the invention is shown in a form of embodiment suitable for use in vehicle body of standard construction, and in which are used pillars of the usual straight form shown, and having a plain front and rear surface. In the frame construction of a car body of the type referred to, the spaced pillars 1 and 1, as shown in Figure 7, have their upper ends secured to 60 the longitudinal girth plate 2, and their lower portions are secured to the side plate 3, and to the floor structure 4. The girth plate and the side plate have the integrally formed drip molds 5 and 6 respectively. At a suitable 65 height is the horizontal seat board 7 which is disposed at a suitable height above the floor.

The present invention, broadly stated, contemplates the combination with the post members or pillars, of channels to retain the vertical edges of the window sash, the said channels being adapted to be urged yieldingly toward each other, and being of width greater at their lower portions than at their upper portions. To carry the invention into effect I provide a 70 resilient sheet metal plate of length equal to substantially twice the height of the sash to be accommodated, and which said plate is adapted to be secured in its central portion, 75 to the pillar. In each of the side portions of the plate, is formed a longitudinal channel or groove, whose sides are divergent, and the width of which channel is greater at its lower than at its upper end. The anterior side of the channel is parallel or coincident with the 80 edge of the plate. The lateral portions of the plate and in which portions the said channels are formed, are bent on lines parallel to the anterior sides of the channels, and at such angles to the transverse axis of the plate, 85 that the seats of the channels are slightly divergent. It is preferable that the said ends shall be at such angles that the inclines of the channels may be substantially of the degrees as shown in Figure 3.

100 The structure just described may be designated as a sash retainer and pillar casement. For the accommodation of a window sash of the size shown herein, which is three eighths of an inch in thickness, twenty seven inches in width, and about twenty inches in height, the length of this sash retainer and casement is about thirty eight inches. It is fashioned from a resilient sheet metal plate, preferably of brass of about number twenty six gauge, 105 and which plate, in its form as a blank, is about six inches in width. By the process of press-

ing or stamping, there is impressed in each of the side portions of this plate, a longitudinal channel, the width of whose seat 10 at its upper portion is about one half of an inch, and 5 at its lower portion is about three quarters of an inch.

The marginal or edge portion of the plate constitutes the anterior side 11 of this channel. 12 designates the interior side of the channel. The bending of the side portions of the plate in the formation of these channels is such, that the sides of the channels are divergent, as shown in the sectional plan view in Figure 3.

15 The lateral portions of the plate are bent on lines which are parallel to the edges of the sides 11 of the channels, and at such angles to the transverse axis of the plate, that the seats 10 of the channels are slightly divergent to each other, as shown in Figure 3.

20 Holes 15 in the central portion of the plate, and spaced as shown in Figure 1, permit of the insertion of suitable cap screws 16, by which the casement is secured to the pillar, 25 as shown in Figure 7.

To equip a vehicle body structure with my invention, the sash is disposed in its lowermost position, at rest on the seat beard 7, or upon such other ledge or stop device as 30 may be provided therefor. Between the edges 17 and 18 of the sashes of adjacent window openings, the side portions of the casement occupy the repressed positions as shown in Figure 6. The casements are then disposed 35 at the desired height, as shown in Figure 7, and in Figure 5, and are simply secured to the pillar, by cap-screws 16, their installation thus being complete. Upon the exterior face of the pillar, is secured a flat metal 40 plate 20 which constitutes a suitable sheathing or finish for the pillar or post member, as shown in Figures 6 and 8.

The manner in which this improved retainer and casement device operates to effectively retain the sash, may be readily understood by reference to Figures 5 and 6. When the sash is at the raised position and with its support catch 19 engaged on the lip 6^a of the drip mold 6 of the side plate 3, the 45 sash frame will have strained the channels toward each other, the edges of the sash being at engagement with the sides 11 of the channels. The window opening thus is 50 closed, and the effect of the pressure of the channels against the edges of the sash, is to 55 hold same tightly against vibration.

To lower the sash it is first lifted slightly and moved inwardly, sufficiently to have disengaged the catch 19 from the lip 6^a of the side plate. The effect then of the pressure of 60 the channels against the edges of the sash, is to cause a tendency of the sash to move to-

ward the sides 12 of the channels; and as the sash, by gravity, moves downwardly, the pressure of the seats of the channels is exerted 65 uniformly and in such manner that while the sash is permitted to move freely, all tendency toward vibration is overcome. The sash, when lowered, occupies the position as indicated by the dotted lines in Figure 5.

70 I am aware that variation and modification of the structure embodying my invention may be made, in rendering same available for frame and sash construction of various forms and styles, without departing from the spirit 75 of the invention as same is defined in the appended claims.

What I claim as my invention, and desire to secure by Letters Patent, is:—

1. A window sash retainer casement section, comprising a resilient channel shaped plate adapted to have the body portion secured to the inner face of the pillar, and having a longitudinal channel formed in each of its side portions, each channel being of width greater at one end than at the other end, and one side of said channel being parallel with the edge of said side portion, each of said side portions being bent on a line parallel with the longitudinal edge thereof so that the 90 seats of the channels on their transverse axes are slightly divergent from each other.

2. In vehicle body construction, the combination with the post member of the window structure, of a resilient channel shaped plate 95 having a longitudinal channel formed in its side portion, the sides of said channel being divergent from the seat of the channel, and said channel being of width greater at its upper end than at its lower end, the said side portion being bent on a line parallel with one of the sides of the channel, and at an angle transverse to the longitudinal axis of the plate.

3. In combination with the pillar, girth 105 plate, side plate, and seat board of the vehicle body, a resilient plate substantially U shape in cross section having a longitudinal channel formed in each of its side portions, each channel being of width greater 110 at its lower end than at its upper end, the seats of said channels on their transverse axes being divergent from each other, the said resilient plate being adapted to be secured at its central portion to the inner face 115 of the pillar and extending from a plane above the bottom of the girth plate to a plane approximately near the plane of the seat board, and a plate secured to the outer face 120 of the pillar and being of width to constitute abutments for the free edges of the sash retainer plate.

RALPH W. JENKINS
